UNITED STATES PATENT OFFICE

2,636,710

DRAPEY SUPPORT AND ELEVATOR

Ethel I. Reuland, Aurora, Ill.

Application August 24, 1951, Serial No. 243,534

3 Claims. (Cl. 248—258)

1

This invention relates to curtain or drapery supports, and more particularly to a support which is attachable to window trim and is effective to support curtains or drapes at different levels including a lower level within convenient reach of a person standing on a floor below the corresponding window for mounting and arranging curtains or drapes on the support, and an upper level at which the curtains or drapes are supported at the proper height relative to the associated window.

It is among the objects of the invention to provide an improved curtain or drapery support which can be readily attached to the trim adjacent a window and will extend from the top of the window trim to a level within convenient reach of a person standing on a floor below the window; which includes a track or guideway structure fixedly attached to the window trim and a curtain or drapery support movable along the guideway from a lower level at which the support is within convenient reach of a person standing on an adjacent floor, and an upper level at which curtains or drapes are positioned at the proper height relative to the associated window; which includes locking means for releasably holding the support in various intermediate positions relative to the guideway so that the supports at opposite sides of a window can be alternately elevated in a step-by-step manner when a curtain rod extends across the window and is connected at its ends to both supports; which will carry either glass curtains or side drapes or both; which can be adjustably extended from the window trim in a direction away from the associated window to maintain the light-admitting area of the window substantially at its maximum width; which provides a safe, sturdy and rigid support for curtains and drapes; and which is simple and durable in construction, economical to manufacture, easy to install and use, and neat and attractive in appearance.

Other objects and advantages will become apparent from a consideration of the following description and the appended claims in conjunction with the accompanying drawings, wherein:

Figure 1 is a side elevational view of a window drape support and elevator illustrative of the invention, shown attached to a window trim fragmentarily illustrated in side elevation;

Figure 2 is a front elevational view of the support and elevator illustrated in Figure 1, shown attached to a window trim fragmentarily illustrated in front elevation;

2

Figure 3 is a top plan view of the support and elevator illustrated in Figures 1 and 2 with the associated window trim and building wall fragmentarily illustrated;

5 Figure 4 is a perspective view of the support and elevator and fragmentary portion of the associated window trim;

Figure 5 is a cross-sectional view of the support and elevator taken on the line 5—5 of Figure 1;

10 Figure 6 is a cross-sectional view on the line 6—6 of Figure 2;

Figure 7 is a cross-sectional view of the fragmentary lower portion of the mechanism illustrated in Figure 6, showing the parts in a different relative position from that illustrated in Figure 6;

15 Figure 8 is a perspective view of a fragmentary portion of a guide bar constituting an operative component of the device;

Figure 9 is a perspective view of a socket structure constituting an operative component of the device;

20 Figure 10 is a perspective view of a latch plate constituting an operative component of the device; and

Figure 11 is a perspective view of a curtain rod supporting bracket also constituting an operative component of the device.

25 With continued reference to the drawings, the drapery support and elevator therein illustrated comprises, in general, a track or guideway structure 10, a support bracket 11 slidably mounted on the guideway structure for movement longitudinally of the latter, a socket structure 12 carried by the bracket structure 11 near one end of the latter, a drapery-supporting arm 13 connected at one end to the socket structure 12 and projecting therefrom substantially perpendicular to the bracket 11, a brace 14 connected between the arm 13 and the bracket 11 at a location spaced from the socket structure 12, and latch plates 15 carried by the bracket and engageable with the guideway structure for releasably locking the bracket at selected positions of longitudinal adjustment relative to the guideway structure.

30 The guideway structure comprises a pair of elongated, flat bars 16 and 17 disposed in spaced apart and substantially parallel relationship and transversely perpendicular to each other, and transverse arms 18 and 19 disposed at the respectively opposite ends of the bars 16 and 17 and each connected at its ends to the inner or adjacent edges of the bars 16 and 17 and extending

3

between these bars. Each of the arms 18 and 19 has a right angular bend intermediate its length, as is clearly illustrated in Figure 4.

The bracket bars 16 and 17 have notches, as indicated at 20 and 21 respectively, spaced apart along one edge thereof, the notches in the bar 16 being illustrated as along the edge of this bar remote from the arms 18 and 19, and the notches 21 in bar 17 being illustrated as disposed along the edge of this bar adjacent the arms 18 and 19. The bar 16 has a slot 22 extending longitudinally thereof from a location adjacent the arm 19 to a location adjacent the arm 18 and the bar 17 has a corresponding slot 23. At its ends the bar 16 is provided with apertured, offset ears 24 and 25, and the bar 17 is provided at its ends with corresponding apertured ears 26 and 27. These offset ears are adapted to bear against the surface of a window trim strip 28, the ears 26 and 27 on the bar 17 bearing against the outside edge surface of the side strip of the window trim with the ear 26 at the top of the trim and the ears 24 and 25 bearing against the front surface of the trim strip with the ear 24 at the top of the trim. These ears are secured to the window trim by suitable fasteners, such as the wood screws 29, extending through the apertures in the ears and threaded into the associated window trim strip.

The bracket 11 comprises a pair of elongated, flat bars 30 and 31 disposed in spaced apart and substantially parallel relationship and transversely perpendicular to each other, these bars being superposed respectively on the outer sides of the guideway bars 16 and 17 when the bracket is operatively mounted on the guideway.

An arm 32 extends between the bars 30 and 31 and is connected at its ends to the inner edges of these bars at the normally lower or bottom end of the bracket and has a right-angled bend intermediate its length. The socket structure 12 includes an arm or strip 33 which extends between the inner edges of the bars 30 and 31 at the normally top or upper end of the bracket and has a right-angled bend intermediate its length. The strip 33 is laterally extended at its ends and provided with rolled formations arranged in opposed pairs, as indicated at 34 and 35 and 36 and 37. The rolled formations 34 and 35 constitute one pair and are spaced apart longitudinally of the bar 30 and provide inwardly opening grooves extending transversely of the adjacent bracket bar while the formations 36 and 37 are spaced apart longitudinally of the bracket bar 31 and provide inwardly opening grooves extending transversely of this bracket bar.

The bracket bars 30 and 31 are each provided with a longitudinally extending slot, as indicated at 38 and 39, respectively, and with rectangularly offset formations, as indicated at 40, for the bar 30, and 41, for the bar 31, spaced apart longitudinally of the corresponding bars and providing slideways for the latch plates 15.

The bar 30 is also provided with an offset handle formation 42 at the normally bottom end of the bracket 11.

Each of the latch plates 15, as is particularly illustrated in Figure 10, comprises an intermediate portion 43 of rectangular shape, a tongue portion 44 of rectangular shape projecting perpendicularly from the intermediate portion at one end of the latter, and a handle-providing ear portion 45 of substantially semicircular shape projecting perpendicularly from the intermediate portion at the end of the intermediate portion remote from the tongue 44 and in a direction op-

4

posite to the tongue. The intermediate portion 43 is provided with a medially disposed slot 46 extending longitudinally thereof between the tongue portion 44 and the ear portion 45.

5 A latch plate is slidably mounted in each of the guideway formations 40 and 41 of the bracket bars 30 and 31, and rivets, as generally indicated at 47, extend one through the slot 46 of each latch plate and through the longitudinally extending slots of the corresponding guideway and bracket bars. Each of the rivets 47 is headed at both ends, as is particularly illustrated in Figure 7, and washers 48 and 49 are disposed on each rivet, one at each end thereof, the washer 48 underlying the associated guideway bar and the washer 49 overlying the corresponding slideway formation of the associated bracket bar, so that the bracket bars are connected to the guideway bars for sliding movement longitudinally of the latter and the latch bars are connected to the bracket bars for sliding movement transversely of the latter.

25 The tongues 44 of the latch bars 15 are selectively engageable in the notches 20 and 21 in the guideway bars 16 and 17 upon sliding the tongues relatively to the corresponding bracket bars 30 and 31, to hold the bracket in selected positions of longitudinal adjustment relative to the guideway.

30 A stop screw 50 is threaded through a tapped hole in the arm 33 of the socket structure 12 and is engageable with the bottom arm 19 of the guideway to prevent accidental separation of the bracket and the guideway. This screw can be threaded outwardly to pass the arm 19 when it is desired to intentionally separate the bracket from the guideway.

35 The drapery support 13 includes an elongated, flat arm 51 having at one end a foot formation 52 disposed at right angles to the arm and extending laterally therebeyond at both sides of the arm, this foot formation having its ends received in the groove-providing formations 36 and 37 of the socket structure to support the arm 51 in a position in which it extends perpendicularly from the bar 31 of the bracket structure in a direction away from the associated window. This support further includes an arm 53 which is superposed on and overlaps the arm 51 and is provided with a slot 54 extending longitudinally thereof. Rivets 55 and 56 are secured in the arm 51 and extend through the slot 54 in the arm 53 to connect the arm 53 to the arm 51 for longitudinal sliding movement of the former relative to the latter. At its end adjacent the end of arm 51 remote from the bracket structure the arm 53 is provided with a socket formation including rolled-over or beaded portions 57 and 58 disposed one at each side of the arm 53 and spaced from the corresponding sides of this arm. The formations 57 and 58 provide opposed, inwardly opening grooves which receive a rectangular foot 59 on a curtain rod-supporting element 60, which element further includes an intermediate portion 61 extending perpendicularly from one edge of the rectangular foot portion 59 and an end portion 62 extending perpendicularly from the end of the intermediate portion 61 remote from the foot portion in the same direction as the foot portion and disposed in spaced and substantially parallel relationship to the foot portion. The end portion 62 is adapted to receive one end of a drapery rod or curtain rod 63 of well known construction.

70 Where curtain rods having curved ends are used, a different rod-supporting element is pro-

vided in which the end portion 62 is omitted and the end of the curtain rod receives the portion 61 of the element.

A lug structure 65 is secured to the bracket bar 31 between the socket structure 12 and the bar-connecting arm 32 and is provided with an aperture near its outer end. The brace link 14 is pivotally connected at one end to the lug structure 65 by a bolt 66 extending through the aperture in the lug structure and through a corresponding aperture in the brace link and is received at its other end in an offset formation 67 provided in the arm 53 intermediate the length of the latter. A bolt 68 extends through an aperture in the brace link and through the slot 54 in the arm 53 to pivotally secure the brace link at its corresponding end to the arm 53, so that the brace supports the drapery support structure 13 in its operative position substantially perpendicular to the bar 31 of the bracket structure 11.

The support and elevator assembly is duplicated at the other side of the window and includes a drapery support extending along the wall in a direction away from the window, so that the side drapes are supported one at each side of the window with their inner edges adjacent the inner edges of the vertical strips of the window trim. The side drapes supported on the drapery-supporting elements of the assembly thus cover the sides of the window trim and the support and elevator assemblies, but do not cover any substantial portion of the window area, leaving the major portion of this area open for the admission of light therethrough.

When it is desired to mount a glass curtain to cover the window area between the side drapes, a curtain rod-supporting element 70, as particularly illustrated in Figure 11, is mounted on the bracket structure. This element 70 has a rectangular foot portion 71, the ends of which are received in the groove-providing formations 34 and 35 of the socket structure 12, and an arm portion 72 extending perpendicularly from the foot portion in a direction away from the bar 39 of the bracket structure and adapted to receive an end of a curtain rod having curved end portions.

If desired, screws 73 and 74 are threaded through tapped holes in the foot portions 59 and 71, respectively, of the supporting elements 69 and 70 to secure the supporting elements to the socket structure when the screws are threaded inwardly of the corresponding foot portions.

In order to install the device, the guideway structure 10 is first mounted on the window trim by the screws 29 in the manner indicated above. The bracket structure 11 is then slid onto the guideway structure by sliding the washers 48 on the rivets 47 through the open bottom ends of the slots 22 and 23 in the guideway bars 20 and 21. After the intermediate portion or arm 33 of the socket structure 12 has been brought above the bottom arm 19 of the guideway structure, the stop screw 50 is threaded inwardly to preclude separation of the guideway and bracket structures.

In order to mount a drape on the support and elevator assembly, with the bracket structure 11 held at a height within convenient reach of a person standing on the floor below the assembly, by engaging the tongue of at least one of the latch plates 15 in a selected notch in one of the bars of the guideway structure, the drape is mounted on the drape or curtain rod 63 supported by the support structure 13 and the supported

end of the drape is arranged as desired. The stop screw 50 is threaded outwardly to clear the top leg 18, the handle 42 is then grasped by one hand of the person mounting the drape, and the latch plate is disengaged from the selected notch in the guideway bar and the bracket is raised to its top position relative to the guideway structure. At least one of the latch plates is then moved to re-engage its tongue in the adjacent notch of the guideway structure to hold the bracket in its uppermost position relative to the associated guideway structure.

When a glass curtain is used so that the rod for this curtain extends between the two brackets mounted at the opposite sides of a window, one of the brackets is raised a limited amount and latched in position and the other bracket is then raised to a position somewhat above the first-moved bracket and latched in position. The first-moved bracket is then again raised a limited amount, the two brackets being successively raised in a step-by-step manner so that the rod supporting the glass curtain does not become disengaged from either of the bracket structures.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A drapery support and elevator assembly comprising a guideway structure including elongated bars disposed in spaced apart and substantially parallel relationship and transversely perpendicular to each other and arms extending between said bars adjacent the ends thereof and each having a right-angled bend intermediate its length, each of said bars having a slot extending longitudinally thereof from one end to a location adjacent the other end and having spaced apart notches in one edge and offset apertured ears disposed one at each end thereof for receiving fasteners to secure said guideway structure to a window trim strip, said guideway structure being mountable on a window trim strip with one end at the stop of the window trim and said bars depending vertically from the top of the window trim one along the face and one along the outside edge of the associated vertical trim strip, a support bracket slidably mounted on said guideway structure and including elongated bars superposed one on each of said guideway structure bars and arms extending between said bracket bars adjacent the ends thereof and each having a right-angular bend intermediate its length, each of said bracket bars having a slot extending longitudinally thereof and slideway formations spaced apart longitudinally thereof and at least one of said bracket bars having an offset handle formation at one end thereof, latch plates slidably disposed one in each of said guideway formations and each having a tongue on one end selectively engageable in the notches in the adjacent guideway bar, a handle-providing ear on its other end and a slot extending between the tongue and the ear, fasteners extending one through each latch plate and through the corresponding bracket and guideway bars for connecting said latch plates to said bracket bars for

sliding movement transversely of the latter and said bracket bars to said guideway bars for sliding movement of said bracket longitudinally of said guideway structure, and a drapery-supporting arm detachably connected at one end to said bracket and projecting outwardly thereof substantially perpendicular thereto.

2. A drapery support and elevator assembly comprising a guideway structure including elongated bars disposed in spaced apart and substantially parallel relationship and transversely perpendicular to each other and arms extending between said bars adjacent the ends thereof and each having a right-angled bend intermediate its length, each of said bars having a slot extending longitudinally thereof from one end to a location adjacent the other end and having spaced apart notches in one edge and offset apertured ears disposed one at each end thereof for receiving fasteners to secure said guideway structure to a window trim strip, said guideway structure being mountable on a window trim strip with one end at the top of the window trim and said bars depending vertically from the top of the window trim one along the face and one along the outside edge of the associated vertical trim strip, a support bracket slidably mounted on said guideway structure and including elongated bars superposed one on each of said guideway structure bars and arms extending between said bracket bars adjacent the ends thereof and each having a right-angular bend intermediate its length, each of said bracket bars having a slot extending longitudinally thereof and slideway formations spaced apart longitudinally thereof and at least one of said bracket bars having an offset handle formation at one end thereof, latch plates slidably disposed one in each of said guideway formations and each having a tongue on one end selectively engageable in the notches in the adjacent guideway bar, a handle-providing ear on its other end and a slot extending between the tongue and the ear, fasteners extending one through each latch plate and through the corresponding bracket and guideway bars for connecting said latch plates to said bracket bars for sliding movement transversely of the latter and said bracket bars to said guideway bars for sliding movement of said bracket longitudinally of said guideway structure, a socket structure mounted on said bracket near the end thereof remote from said handle, a first arm engaged at one end in said socket structure and extending perpendicularly from said bracket, a second arm superposed on said first arm in overlapping relationship thereto, means interconnecting said arm for relative longitudinal sliding movement, a lug extending from said bracket at a location spaced from said first arm, a brace connected between

said lug and said second arm for supporting said first and second arms substantially perpendicular to said bracket, a socket structure on the end of said second arm remote from said bracket, and a curtain rod-engaging element mounted at one end in the last-mentioned socket structure.

3. A drapery support and elevator assembly comprising an elongated guideway structure adapted to be mounted on a window trim with one end at the top of the trim and with said guideway structure depending from the top of the trim along the outer vertical edge thereof, an elongated bracket structure superposed on said guideway structure in overlapping relationship thereto, means connecting said bracket structure to said guideway structure for longitudinal sliding movement of the former relative to the latter, said bracket structure being vertically movable when said guideway structure is operatively mounted on a window trim, means carried by one of said structures and engageable with the other at selected locations therealong to releasably lock said structures in selected positions of longitudinal adjustment relative to each other, and a curtain rod-supporting assembly extending perpendicularly from said bracket structure at the normally upper end of the latter, said guideway structure and said bracket structure both including two longitudinally extending portions disposed at right angles to each other and in spaced apart and substantially parallel relationship and adapted to respectively overlie the front face and the outside edge of an associated window trim strip, and said curtain rod-supporting assembly including a first socket mounted on said bracket structure at the normally upper end of the portion of the latter adapted to overlie the outside edge of an associated window trim strip, an adjustable length arm assembly engaged at one end in said first socket and extending perpendicularly from the associated portion of said bracket structure, a second socket on the other end of said arm assembly, a curtain rod-engaging element engaged at one end in said second socket, and a brace connected between said arm assembly at a location intermediate the length of the latter and said associated bracket portion at a location spaced from said first socket.
